METHOD OF AND MACHINE FOR OPERATING ON INSOLES

Hans C. Paulsen, Medford, Mass., assignor to
United Shoe Machinery Corporation, Flemington, N. J., a corporation of New Jersey

Application March 1, 1943, Serial No. 477,547

24 Claims. (Cl. 12—20)

This invention relates to methods of and machines for applying reinforcing tapes or strips of material, for example canvas, to insoles and is disclosed with particular reference to the reinforcement of ribbed or welt insoles, the reinforcing strip being applied only to the inner face of the rib and the adjacent body of the insole.

Objects of the invention are so to apply the strip that distortion of the insole will not result, to produce an improved article, and to provide apparatus by which the improved results may be obtained.

The invention, while retaining the valuable aspects of the method and features of the machine disclosed respectively in Letters Patent of the United States No. 2,255,353 granted September 9, 1941, in the name of Stanley M. Griswold, and No. 2,242,248 granted May 20, 1941, in the names of Stanley M. Griswold and Russell K. Nash, provides a method and apparatus by the use of which improved results are obtained in that distortion of the insole is avoided without special attention on the part of the operator.

The invention, in its method aspect, consists in fulling the strip as it is applied to the insole. As illustrated, a portion of the strip is applied to the inner face of the rib, and another portion of the strip is applied to the body portion of the insole adjacent to the rib. In applying the strip in accordance with the present invention, the portion of the strip which lies adjacent to the angle between the inner face of the rib and the body of the insole is urged toward the point of application, with the result that longitudinal tension on the strip is relieved and the insole remains in the same shape it had before application of the strip; that is, the insole is undistorted.

The invention, in its machine aspect, is illustrated as embodied in a machine of the type disclosed in the Griswold and Nash patent above referred to, the machine, however, embodying the improvements disclosed in Letters Patent of the United States No. 2,335,289, granted November 30, 1943, in the name of Norman E. Mariner. Machines of this type are provided, as shown herein, with a lower feed roll engaging the unribbed face of the insole and an upper feed roll engaging the feather of the insole and supporting the outer face of the rib. An applying device comprising a roll acts to lay one marginal portion of the reinforcing strip against the body of the insole adjacent to the rib and means carried by the applying device lays the other marginal portion of the strip against the inner face of the rib, the applying device being mounted

on an arm of a manually operated rockshaft for movement into and out of operative position.

I have found that better results are obtained by driving the applying roll which previously has been freely rotatable and that still better results are obtained by driving the applying roll at a peripheral speed in excess of that imparted to the feed rolls. To this end, the applying roll is provided with gear teeth and is driven by suitable gearing connected to the main shaft of the machine.

The gear teeth may be formed on that end of the applying roll which is nearer to the rib of the insole and may serve in place of spurs to feed the strip while the feed rolls feed the insole. When the applying roll is driven at a peripheral speed in excess of that of the feed rolls, the gear teeth thereon act to full the strip or urge it in the direction of feed, thus relieving tension on the strip at the point of application with the result that distortion of the insole is avoided. Instead of the applying roll being formed in sections, as in prior machines, it may be in one piece or solid, in which case gear teeth may be formed on the end of the roll more remote from the rib, and teeth or spurs of any desired kind may be formed on the end of the roll adjacent to the rib to enhance its feeding action at that point.

It is important that pressure be applied to the strip both by the part of the applying roll which engages the strip over the channel and by the part of the roll which engages the strip inwardly beyond the channel, and hence it is desirable that the two parts of the roll be arranged to yield relatively to each other and that at least one of the parts be driven to produce the fulling effect. Accordingly, as illustrated, the applying device comprises two rolls one of which applies the strip at the base of the rib and over the channel and may be termed the channel roll or base roll and a roll which engages the strip over the body of the insole and may be termed the body roll. The base roll is mounted on a lever which is urged by a spring toward the insole, means being provided to vary the initial position of the roll, the tension of the spring and the amount the lever can yield in response to the applying pressure. Means is provided for driving the body roll which has a connection between it and the base roll whereby the base roll is also driven notwithstanding its capacity for movement out of axial alignment with the body roll which is driven. This connection, as illustrated, comprises radial lugs on one of the rolls which engage radial grooves in the other.

These and other features and aspects of the invention will appear more fully from the following description when read in connection with the accompanying drawings and will be pointed out in the appended claims.

In the drawings,

Fig. 1 is a side elevation, partly in section, of the machine embodying the invention;

Fig. 2 is a front elevation of the mechanism for operating the applying roll;

Fig. 3 is an elevation, partly in section, showing the applying roll, the gear which drives it and the strip guide;

Fig. 4 is a plan view, partly in section, of the applying roll and its driving mechanism;

Fig. 5 is a view, similar to Fig. 4, showing a modified form of applying roll;

Fig. 6 is a view, partly in section, of the feed rolls and an applying device in the act of laying a reinforcing strip upon the insole;

Fig. 7 is a view of an insole after being operated upon by the machine and in accordance with the present method;

Fig. 8 is a front elevation of the head of the machine showing a further modified form of applying roll in operative position;

Fig. 9 is an elevation, partly in section on the line IX-IX of Fig. 16, of the applying device shown in Fig. 8;

Fig. 10 is an elevation of the rear side of the applying device removed from the machine;

Fig. 11 is a similar view with the lever which carries the base roll removed;

Fig. 12 is an elevation of the front side of the applying device;

Figs. 13 and 14 are details showing opposite sides, respectively, of the lever which carries the base roll;

Figs. 15 and 16 are, respectively, elevations taken from opposite sides of the assembled applying device;

Figs. 17 and 18 are end views, respectively, of the adjacent ends of the base roll and body roll; and Fig. 19 is a detail of a stud associated with the part shown in Figs. 13 and 14.

Referring to Fig. 1, the head of the machine comprises a frame 10 in which is mounted in suitable bearings a main drive shaft 12. On the rear end of the shaft is fixed a pulley 14 driven by a belt 16 from a suitable source of power and a lower feed roll 18 is secured to the front end of the shaft. Above the shaft 12 is mounted a shaft 20 on the front end of which is an upper feed roll 22 and on the rear end of which is fixed a gear 24 which meshes with a similar gear 26 fixed to the main shaft 12. The shaft 20 has front and rear bearings in a yoke 28 pivoted at 30 to permit the upper feed roll to be raised and lowered. Above the shaft 20 is a rockshaft 32 on which is an arm 34 connected to a treadle rod 36. The rockshaft 32 is connected by means including a link 38 to the yoke 28 so that a downward pull on the treadle rod 36 will yieldingly depress the feed roll 22 against the insole supported by the lower feed roll 18. By the same movement of the rockshaft 32 an applying roll 40 which is mounted on an arm 42 secured to the rockshaft is brought into cooperative relation to the feed rolls 18, 22.

The above and other parts of the machine not herein described are constructed and arranged as disclosed in the Mariner patent referred to above.

In the illustrated embodiment of the present invention the rockshaft 32 is hollow or sleeve-like and through it extends a shaft 50 on the

rear end of which is secured by a setscrew 52 a sprocket wheel 54. A similar sprocket 56 is secured in a similar manner to the main shaft 12 and these sprockets are connected by a chain 58. The sprocket 56 is larger and has more teeth than the sprocket 54 and hence the shaft 50 will be driven at a speed slightly in excess of that of the shaft 12. On the front end of the shaft 50 is pinned a sprocket 60 (Fig. 2) connected by a chain 62 to a sprocket 64 having the same number of teeth as the sprocket 60. The sprocket 64 is pinned to a shaft 66 having a bearing in the arm 42 formed by a bushing 68. At its rear end the shaft 66 (Fig. 4) has fixed thereto a gear 70 which meshes with gear teeth 72 formed on the applying roll 40, the teeth 72 being similar in number to those on the gear 70. Thus, the applying roll will be driven at a speed depending on the ratio of the number of teeth on the sprocket 56 to the number of teeth on the sprocket 54 which may be readily removed and replaced by a sprocket having a different number of teeth. Preferably a sprocket 54 will be selected which has a number of teeth such that the applying roll 40 will be driven at a peripheral speed somewhat in excess of that of the feed roll 22, the applying roll and the feed roll 22 rotating, of course, in the same direction.

To give the applying roll traction on a strip S, the rear end of this roll, that is, the end which is nearer to the rib of the insole, is provided with teeth or spurs 74 (Fig. 4) so that, since the peripheral speed of the applying roll is greater than that of the feed rolls, the portion of the reinforcing strip engaged by the teeth 74 will be urged in the direction of feed faster than the feed can take place. Thus, not only is any longitudinal tension on the strip neutralized, but a fulling or slight lengthwise compression of the strip occurs but not to such an extent as would form wrinkles therein. This results in the strip being applied to the insole in a flat and smooth condition even where the rib of the insole curves inwardly or outwardly with respect to the inner part of the insole. As usual, the applying roll is held on a fixed stud shaft 76 (Fig. 3) by a disk or head 78 (Fig. 4) formed on the shaft, this head engaging the marginal portion of the strip which is laid against the inner face of the rib and rubbing it into firm contact therewith while the teeth 74 roll and pack the central portion of the strip against the insole at the base of the rib and the remainder of the applying roll, including the teeth 72, rolls the inner marginal portion of the strip against the body of the insole. It will be noted that the toothed portion 74 of the applying roll is somewhat larger in diameter than the remainder of the roll so as to extend into the channel of the insole from which the inner lip forming part of the rib was cut and turned up, thus allowing the portion of the roll having a smaller diameter to engage the strip. It is to be understood that as usual in machines of this type the applying device, when in operative position, is urged toward the rib by a spring 79 on the rockshaft 32 to cause the head 78 to rub the strip against the inner face of the rib.

In Fig. 5 a modification of the applying roll 40 is shown. In this case the applying roll 40' has gear teeth 80 on the end adjacent to the head 78 and the gear 70 is reversed in position so as to mesh with the teeth 80. The teeth 80 are formed on a part of the roll 40' which is slightly larger than the remainder of the roll so that the teeth 80 reach down into the channel and permit

the remaining portion of the roll, which is smooth, to engage the portion of the strip *S* which is laid against the body of the insole. In this construction the gear teeth *80* serve not only to drive the roll but also to provide the tractive and fulling effect produced by the teeth *74* on the roll *40* (Fig. 4).

To provide an applying roll the channel-engaging portion of which may yield heightwise of the rib so that both portions of the roll will engage the strip notwithstanding variations in the depth of the channel and to still provide for driving both sections of the roll, the construction shown in Figs. 6 and 8 to 19 was developed.

In the Mariner patent above referred to, a sectional roll is disclosed one section of which is yielding with respect to the others but none of the sections is driven.

The rear side of the applying roll assembly is shown in Fig. 10 and comprises a frame member *90* to which is pivoted by a headed stud *92* an angle lever *94*. The stud *92* (Fig. 19) passes through a hole *93* in the lever and into a hole *35* in the member *90*, the stud having a flattened side *96* which is engaged by a setscrew *98* (Fig. 10) to hold the lever *94* in position, the head of the stud *92* being received in a counterbore *160* formed in the lever *94* (Fig. 14). On its front face, as shown in Fig. 13, the angle lever *94* is provided with a stud *102* which receives a section *104* (Fig. 17) of the applying roll which applies a portion of the tape to the channel of the insole at the base of the rib and is called herein the base or channel roll. The stud *102* has a length corresponding to the thickness of the roll section *104* and on the face of the roll, which is adjacent to another section *106* of the roll, three radial grooves *108* are formed, the grooves being arranged 120° apart. The section *106* of the applying roll, as shown in Fig. 18, is provided with radial projections *110* arranged in positions corresponding to those of the radial grooves *108* into which they fit loosely when the roll sections *104*, *106* are assembled in the relation shown in Fig. 15. The roll *106* applies a portion of the strip to the body of the insole and is termed herein the body roll. The front portion of the section *106* is provided with gear teeth *112* which, when this modified applying roll assembly is mounted on the machine, mesh with the teeth of the gear *70* on the shaft *66*. The section *106* of the applying roll is mounted on a stud *114* which passes through a hole in the frame member *90*, is held from turning by a pin *118* entering a notch in the frame *90* (Fig. 11) and is held in place by a nut *120*, the stud being long enough to provide a suitable bearing for the roll *106* without engaging the stud *102* on which the roll section *104* is mounted. The lugs *110*, however, engage the grooves *108* and drive the roll section *104* while permitting a limited amount of displacement of the axis (stud *102*) of the roll section *104* with respect to the axis (stud *114*) of the roll section *106*.

From Fig. 8, which shows this form of applying device in the position it assumes when the machine is operating upon an insole, and from Fig. 9, which is a view partly in section of the device in substantially the same position, it will be seen that pressure of the section *104* of the roll on the work tends to move the lever *94* on which it is mounted in a counterclockwise direction about its fulcrum *92*, which movement is opposed by a spring *122* seated in a recess *123* in the lever *94* and engaging a screw *124* threaded into a lug *126*

on the frame *90*. The position of the roll *104*, when relieved from pressure against an insole, is determined by an adjusting screw *128* threaded through an ear *130* on the lever *94* and engaging the lower face of the lug *126*. This screw, of course, determines the initial position of the roll *104* and is held in adjusted position by a lock nut *132*. The amount the roll section *104* can yield vertically with respect to the section *106* is determined by a stop screw *134* threaded through the lug *126* in position to engage the upper arm of the lever *94* after the spring *122* has yielded a predetermined amount, the screw *134* being held in adjusted position by a lock nut *136*. The initial tension of the spring *122*, that is, the force required to displace the roll section *104* with respect to the roll section *106*, may be varied by adjusting the screw *124* in or out, the screw being held in adjusted position by a set screw *138*.

The member *90* has on its front face a rectangular lug *140* (Fig. 12) which fits into a corresponding recess in the arm *42* where it is held by a dowel pin in a hole *142* and by two screws *143* in holes *144*. The shaft *66* carrying the gear *70* has a bushing *146* similar to the bushing *68* located in a hole *148* in the member *90*, the gear, as indicated in Fig. 9, meshing with the teeth *112* on the roll *106* and both gears *70* and *106* having the same number of teeth.

The fulcrum *92* of the lever *94* is sufficiently in advance of the roll *104* (to the left, Fig. 9) to permit the roll readily to swing upwardly without any binding tendency, and the coupling formed by the interengaged grooves *108* and lugs *110* permits eccentric displacement of the axis of the roll *104* with respect to the axis of the roll *106* without disturbing the driving connection between them. By this construction the reinforcing strip is not only laid against the inner face of the rib but is laid in the channel at the base of the rib and against the body of the insole with adequate pressure to cause adhesion of the strip to the insole irrespective of variations in the depth of the channel; and, since the base roll which applies the strip at the base of the rib is driven at a peripheral speed in excess of that of the feed rolls *18* and *22*, the strip is crowded or fulled and hence distortion of the insole is avoided.

It will be understood from Figs. 3 and 8 that the strip, as in prior machines of this type referred to herein, is led from a reel through an angular strip guide or folder *152* by which the marginal portion of the strip which is to be laid against the rib is bent toward the direction from which the insole is fed and then passes around a curved edge *154* on a plate carried by the folder into a position parallel to the inner face of the insole rib against which it is pressed and rubbed by the head *78* of the applying device of Figs. 4 and 5 or by a surface *156* on the lever *94* carrying the base roll shown in Fig. 10.

As shown in Fig. 6, the upper feed roll *22* may be provided on its feather-engaging face with a portion *150* of slightly greater diameter which is toothed or knurled to increase the grip of the feed roll on the feather of the insole, thus giving the feed rolls better control of the work to oppose the fulling or crowding action of the applying roll when driven at a greater peripheral speed than the feed rolls.

Having thus described my invention, what I claim as new and desire to secure by Letters Patent of the United States is:

1. That improvement in methods of reinforcing ribbed insoles which consists in feeding an

insole, laying a strip of canvas against the inner face of the rib and against the adjacent portion of the body of the insole, and crowding the strip in the direction of feed to prevent distortion of the insole.

2. That improvement in methods of reinforcing ribbed insoles which consists in feeding an insole, laying a strip of canvas against the inner face of the rib and against the adjacent portion of the body of the insole, and crowding the strip in the direction of feed by force applied to the strip in a location adjacent to the angle between the rib and the insole body.

3. That improvement in methods of reinforcing insoles which consists in providing an insole having an upstanding rib with cement on the inner face of the rib and on the adjacent portion of the body of the insole, applying the strip to the inner face of the rib and the body of the insole, and simultaneously fulling the strip.

4. That improvement in methods of reinforcing ribbed insoles which consists in continuously feeding an insole past an operating point, supporting the outer face of the rib, laying one marginal portion of the strip against the body of the insole, forcing another marginal portion of the strip against the inner face of the supported rib, and simultaneously urging the strip endwise in the direction of feed, thus fulling the strip by supplying it faster than it is needed by the feeding of the insole.

5. In a machine for applying a reinforcing strip to ribbed insoles, means for feeding an insole, a roll for applying one marginal portion of the strip to the body of the insole, means for turning the other marginal portion of the strip at right angles to the first-mentioned portion, and means for driving the roll at a peripheral speed in excess of the rate of feed to reduce tension on the strip and thus avoid distortion of the insole.

6. In a machine for reinforcing ribbed insoles, the combination of means for supporting and feeding an insole past an operating point, an applying roll, means for guiding a strip of reinforcing material to the applying roll with a marginal portion thereof directed toward the direction from which the insole is being fed, means adjacent to the applying roll for turning said margin into a position parallel to the inner face of the rib, means for pressing the marginal portion against the rib while the applying roll presses the remainder of the strip against the body of the insole, and means for driving the applying roll at a peripheral speed in excess of the rate at which the insole is fed.

7. In a machine for applying strips of material to insoles, the combination of a pair of feed rolls for guiding and feeding the marginal portion of an insole, one feed roll extending beyond the other to support the insole, means for positively driving the feed rolls continuously, strip-guiding means, an applying roll opposed to the longer feed roll to press the strip upon the adjacent face of the insole as it is fed, and means for driving the applying roll.

8. In a machine for applying strips of material to insoles, the combination of a pair of feed rolls for guiding and feeding the marginal portion of an insole, one feed roll extending beyond the other to support the insole, means for positively driving the feed rolls continuously, strip-guiding means, an applying roll opposed to the longer feed roll to press the strip upon the adjacent face of the insole as it is fed, and means

for driving the applying roll at a peripheral speed in excess of that of the opposed feed roll.

9. In a machine for applying strips of material to insoles, the combination of a pair of feed rolls for feeding the marginal portion of an insole, one roll extending beyond the other to support the insole, means for positively driving said rolls continuously, teeth on the shorter roll to control the rate of feed, and an applying roll driven at a greater peripheral speed than the feed rolls for pressing the strip against the insole.

10. In a machine for applying reinforcing strips to insoles, a pair of opposed driven rolls for feeding the insole, an applying device comprising a plurality of rolls arranged to apply pressure to the same side of a strip, one of said rolls being mounted to yield relatively to the other roll, and means for driving one of the rolls.

11. In a machine for applying reinforcing strips to insoles, a pair of opposed driven rolls for feeding the insole, an applying device comprising a plurality of rolls arranged to apply pressure to the same side of a strip, one of said rolls being mounted to yield relatively to the other roll, and means for driving both rolls.

12. In a machine for applying reinforcing strips to insoles, a pair of opposed driven rolls for feeding the insole, an applying device comprising a plurality of rolls arranged to apply pressure to the same side of a strip, one of said rolls being mounted to yield relatively to the other roll, means for driving one roll, and connections for driving another roll from said driven roll.

13. In a machine for applying reinforcing strips to insoles, a pair of opposed driven rolls for feeding the insole, an applying device comprising a plurality of rolls arranged to apply pressure to the same side of a strip, one of said rolls being mounted to yield relatively to the other roll, means for driving one roll, and interengaging connections for driving another roll from said driven roll.

14. In a machine for applying strips of material to ribbed insoles, a strip-applying device comprising a base roll arranged to lay a portion of the strip against the insole at the base of the rib, means for driving said roll, a body roll arranged substantially in coaxial alinement with the base roll for laying another portion of the strip against the body of the insole, and yielding means permitting movement of the axis of one of said rolls out of alinement with the axis of the other roll.

15. In a machine for applying strips of material to ribbed insoles, a pair of opposed driven rolls for feeding the insole, a base roll arranged to apply a portion of a strip to the insole at the base of the rib, a body roll arranged to apply another portion of the strip to the body of the insole, means for permitting the base roll to yield to pressure against the insole relatively to the body roll and means for driving both rolls.

16. In a machine for applying strips of material to ribbed insoles, a pair of opposed driven rolls for feeding the insole, a base roll arranged to apply a portion of a strip to the insole at the base of the rib, a body roll arranged to apply another portion of the strip to the body of the insole, means for permitting the base roll to yield to pressure against the insole relatively to the body roll, means for driving the body roll, and means for driving the base roll from the body roll.

17. In a machine for applying strips of material to insoles, a strip-applying device comprising a rubbing element arranged to yield in response to pressure against the insole, a stud on said element, a roll mounted for rotation on said stud, said element and roll being adapted to engage the strip over a thinner portion of the insole, a roll mounted independently of the first-mentioned roll with its axis nearly in alinement with that of the first-mentioned roll and arranged to engage the strip over a thicker portion of the insole, and means for driving the roll which engages the strip over the thinner portion of the insole.

18. In a machine for applying strips of material to insoles, a strip-applying device comprising a rubbing element arranged to yield in response to pressure against the insole, a stud on said element, a roll mounted for rotation on said stud, said element and roll being adapted to engage the strip over a thinner portion of the insole, a roll mounted independently of the first-mentioned roll with its axis nearly in alinement with that of the first-mentioned roll and arranged to engage the strip over a thicker portion of the insole, and means for driving the roll which engages the strip over the thicker portion of the insole.

19. In a machine for applying strips of material to insoles, a strip-applying device comprising a rubbing element arranged to yield in response to pressure against the insole, a stud on said element, a roll mounted for rotation on said stud, said element and roll being adapted to engage the strip over a thinner portion of the insole, a roll mounted independently of the first-mentioned roll with its axis nearly in alinement with that of the first-mentioned roll and arranged to engage the strip over a thicker portion of the insole, and means for driving both rolls.

20. In a machine for applying strips of material to insoles, the combination of a pair of feed rolls for feeding the marginal portion of an insole, one feed roll extending beyond the other to support the insole, means for positively driving the feed rolls continuously, strip-guiding means, an applying roll having at least two sections, means permitting one section to yield in response

to pressure on the work, and means for driving one section of the roll.

21. In a machine for applying strips of material to insoles, the combination of a pair of feed rolls for feeding the marginal portion of an insole, one feed roll extending beyond the other to support the insole, means for positively driving the feed rolls continuously, strip-guiding means, an applying roll having at least two sections, means permitting one section to yield in response to pressure on the work, and means for driving both sections of the roll.

22. In a machine for applying a reinforcing strip to ribbed insoles, means for feeding an insole, a roll for applying one marginal portion of the strip to the body of the insole, means for turning the other marginal portion of the strip at right angles to the first-mentioned portion, means for driving the roll at a peripheral speed in excess of the rate of feed to reduce the tension on the strip and thus avoid distortion of the insole, and means for laying the turned marginal portion of the strip against the inner face of the rib.

23. In a machine for reinforcing ribbed insoles, the combination of a pair of opposed driven rolls for supporting and feeding an insole past an operating point, a sectional applying roll, means for driving one section of the applying roll, and connections between said driven section and another section for driving the other section also.

24. In a machine for reinforcing ribbed insoles, the combination of means for supporting and feeding an insole past an operating point, a sectional applying roll, means for guiding a strip of reinforcing material to the applying roll with a marginal portion thereof directed toward the direction from which the insole is fed, means adjacent to the applying roll for turning said margin into a position parallel with the inner face of the rib, means for pressing the turned marginal portion against the rib while the applying roll presses the remainder of the strip against the body of the insole, means for driving one section of the applying roll, and connections between the driven section and another section for driving the other section also.

HANS C. PAULSEN.
